UNITED STATES PATENT OFFICE

152,316

DESIGN FOR A VEHICLE HEATER

Adolph G. Bergstrom, Rockford, Ill.

Application April 29, 1946, Serial No. 129,077

Term of patent 7 years

(Cl. D14—6)

To all whom it may concern:

Be it known that I, Adolph G. Bergstrom, a citizen of the United States, residing at Rockford, in the county of Winnebago and State of Illinois, have invented a new, original, and ornamental Design for Vehicle Heater, of which the following is a specification, reference being had to the accompanying drawing, forming part thereof.

In the drawing:

Fig. 1 is a front view of a vehicle heater, showing my new design, the front and side shutters being shown closed;

Fig. 2 is a plan view of Fig. 1;

Fig. 3 is a side view of Fig. 1, and

Fig. 4 is a front view of the heater, showing the front and side shutters opened.

The back of the heater, which is not shown in the above figures, is substantially plain.

I claim:

The ornamental design for a vehicle heater, substantially as shown and described.

ADOLPH G. BERGSTROM.
